CLAIM

The ornamental design for a glass core atomizer, substantially as shown and described.

DESCRIPTION

FIG. 1 is an upper perspective view of the glass core atomizer.

FIG. 2 is a side perspective view thereof.

FIG. 3 is lower perspective view thereof.

FIG. 4 is a top view thereof.

FIG. 5 is a front view thereof; and,

FIG. 6 is a side view thereof.

1 Claim, 6 Drawing Sheets
